UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

PANTOGRAPH TROLLEY.

Application filed February 15, 1919. Serial No. 277,350.

To all whom it may concern:

Be it known that I, WILLIAM SCHAAKE, a citizen of the United States, and a resident of Pittsburgh, in the county of Allegheny and State of Pennsylvania, have invented a new and useful Improvement in Pantograph Trolleys, of which the following is a specification.

My invention relates to trolleys and particularly to operating means for pantograph trolley frames.

One object of my invention is to provide means whereby a device, of the above indicated character, may be extended and retracted at selectively predetermined speeds.

Another object of my invention is to provide means whereby a momentary reduction in the value of the force exerted between the pantograph frame and the actuating means therefor may be automatically effected, during the actuation of the frame, in order to prevent the violent slamming of the latter, at the end of one of its operating movements.

Heretofore, it has been usual, in the operation of certain pantograph trolley frames, to provide cushioning means, such as springs and dash pots, to arrest the momentum thereof at the ends of the operations of extending and retracting the frames but, to the best of my knowledge, none of these has been entirely satisfactory.

Further, in operating pantograph frames by the usual fluid-pressure cylinder and piston, one value of operating pressure has usually been employed.

In practicing my invention, I provide means whereby the inlet and exhaust ports of a fluid-pressure operating cylinder, for a pantograph frame, may be separately regulated to effect any desired speed in the operation of extending and retracting the frame, by which means certain desirable characteristics in the raising and lowering of pantograph trolley frames may be attained.

I further provide means, at an intermediate point of travel of the operating piston, for automatically and momentarily relieving the pressure thereon, thereby reducing the speed and the momentum of the pantograph frame and permitting it to complete its motion before being able to further accelerate to any great degree and permitting its normal

motion under full pressure near the finish of its travel.

Figure 1 of the accompanying drawings is a diagrammatic side view, partially in elevation and partially in section, of a pantograph trolley embodying my invention and indicating a locomotive or other vehicle on which the trolley may be mounted. Figs. 2 and 3 are, respectively, an elevation and a side section detail view of a modified form of fluid-pressure reducing disc embodied in my invention.

A locomotive 1 pivotally supports, by means of brackets 2 and pins or rods 3, an extensible pantograph frame 4, of usual construction, that supports a contact member 5 for engaging a trolley conductor 6. The frame 4 may be biased toward, and moved to, its extended position by springs 7 extending between stationary brackets 8, disposed on the locomotive 1, and arms 9, rigidly related to the frame 4, and be retracted by co-operating links 10, levers 10^a, and pistons 11 disposed in cylinders 12 connected to a main air reservoir 13 through tubes 4 having a controlling valve 15. A member 16, attached to the frame 4, engages, in the retracted position of the frame, a latching pawl 17 pivoted on a pin 18 and supported by a cylinder 19 that receives a supply of air from the reservoir 13 through tubes 20 and a valve 21. Pressure reducing devices 22 and 23 are located in series relation with the tubes 14 on opposite sides of the operating valve 15, and are of a usual and well known construction, each embodying a removable disc 24 having an opening 25 therein. The valve 15 is adapted to directly connect the cylinders 12 and the reservoir 13, through both of the devices 22 and 23, to lower the frame 4 by the action of the fluid pressure against the pistons 11, arms 9 and links 10, against the tension of the springs 7. The device 22, having a smaller opening 25 through its disc 24, controls the rate of flow of the fluid in lowering the frame 4. An auxiliary reservoir 26, which normally contains fluid at atmospheric pressure is connected, by tubes 27, to the cylinders 12 at intermediate points in the paths of travel of the pistons 11 and, during the operation of retracting the frame 4, the arrangement permits the operating fluid to escape from the fluid pressure side of the

pistons 11 into the reservoir 26 and thereby momentarily reduce the operative fluid pressure to reduce the momentum of the frame before the latter is completely retracted. 5 During this operation, after the fluid in the reservoir 26 has been compressed, the normal operating pressure on the piston 11 will be resumed and the frame will be retracted to its final position without violence. In extending the frame 4, the operating valve 15 is moved to the position indicated in the drawings after which air is admitted to the cylinder 19 by the operation of the valve 21 to release the frame 4 which, during its 10 extending movement, will move the piston 11 and exhaust the cylinders 12 through the member 23 and the operating valve 15 to the atmosphere.

This arrangement permits the frame 4 to 20 be raised and lowered at different speeds of any desired value. In Figs. 2 and 3 is shown an adjustable form of disc device 24* that comprises relatively movable washers 28 and 29 held together by a bolt 30 having 25 a nut 31. The washer 28 is provided with one relatively large opening 32 adapted to be turned to, and fixed in, a position to register with any one of various-sized openings 33 in the washer 29.

30 While I have shown and described a particular form of my invention, changes may be effected therein without departing from the spirit and scope thereof, as set forth in the appended claims.

35 I claim as my invention:

1. In a trolley, the combination with a pantograph frame, of means for extending and retracting said frame at selectively predetermined speeds and for momentarily reducing said retracting speed during the 40 movement of said frame.

2. In a trolley, the combination with a pantograph frame, of fluid-actuated means for extending and retracting said frame at 45 selectively predetermined speeds and for momentarily reducing said retracting speed before said frame reaches its limiting position.

3. In a trolley, the combination with a 50 pantograph frame, of means for extending and retracting said frame at selectively predetermined speeds, said means comprising a fluid-operated actuating mechanism for said frame, a plurality of regulating discs for said mechanism and a controlling valve located between said regulating discs for alternately including and excluding one of the discs as an active element.

4. In a trolley, the combination with a 55 pantograph frame, of means for extending and retracting said frame at selectively predetermined speeds, said means comprising a fluid-operated actuating mechanism for said

frame,* a plurality of regulating discs for said mechanism and a controlling valve located between said regulating discs for selectively including one of the discs as an active element, said regulating discs being adapted for permitting different rates of flow of a fluid therethrough. 70

5. In a trolley, the combination with a pantograph frame, of means for extending and retracting said frame at selectively predetermined speeds, said means comprising a fluid-actuated mechanism for said frame, 75 a fluid source, a disc for regulating the flow of a fluid to said mechanism, a disc for regulating the flow of a fluid from said mechanism, and a valve located between said regulating discs for selectively controlling said 80 regulating discs.

6. In a trolley, the combination with a pantograph frame, of a fluid-pressure means for extending and retracting said frame at selectively predetermined speeds, and fluid-pressure means for momentarily retarding the movement of said frame near the end of 85 one of its movements.

7. In a trolley, the combination with a pantograph frame, of means for extending 90 and retracting said frame at selectively predetermined speeds, said means comprising a fluid-operated actuating mechanism for said frame, a plurality of adjustable regulating discs for said mechanism, and a controlling 95 valve for selectively directing a fluid through said regulating discs.

8. In a trolley, the combination with a pantograph frame, of means for extending and retracting said frame at selectively predetermined speeds, and means for automatically changing one of said speeds momentarily at a predetermined point in the path 100 of movement of said frame.

9. In a trolley, the combination with a 105 pantograph frame, of means for extending and retracting said frame at selectively predetermined speeds, and means for automatically changing one of said speeds momentarily at a predetermined intermediate point 110 in the path of movement of said frame.

10. In a trolley, the combination with a pantograph frame and an actuating cylinder-and-piston therefor, of an actuating fluid-supply reservoir connected to said cylinder, two series-related regulating discs disposed between said reservoir and said cylinder, a controlling valve disposed between said regulating discs, and an auxiliary reservoir connected to said cylinder at an intermediate point in the path of travel of 115 said piston to momentarily relieve the pressure upon said piston and thereby serve as retarding means in the movement of said frame. 120

11. In a trolley, the combination with a 125

pantograph frame, of means for extending and retracting said frame, and means for automatically changing the rate of travel of said frame momentarily at an intermediate stage of one of said movements.

12. In a trolley, the combination with a pantograph frame of fluid-pressure means for extending and retracting said frame, and a means for automatically reducing the fluid pressure at an intermediate stage of one of said movements.

13. In a trolley, the combination with a pantograph frame of fluid-pressure means for extending and retracting said frame, and automatic means for temporarily reducing 15 the fluid pressure at an intermediate stage of one of said movements.

In testimony whereof, I have hereunto subscribed my name this 31st day of Jan., 1919.

WILLIAM SCHAAKE.
